Primary Examiner — Karen S. Acker*Assistant Examiner* — Wendy Arminio(74) *Attorney, Agent, or Firm* — Norton Rose Fulbright US LLP(57) **CLAIM**

The ornamental design for a stand, as shown and described.

DESCRIPTION

FIG. 1 is a top perspective view of a stand showing our new design;

FIG. 2 is a bottom perspective view thereof;

FIG. 3 is a front view thereof, the right and left sides thereof being identical due to the symmetry of the design about its vertical axis; and,

FIG. 4 is a top view thereof.

The stand is intended to be placed on a tray and used as a support for the tray cover and possibly one or more stacked trays, for items such as edible items.

The dashed lines in the figures form no part of the claimed design.
